tion of California

Application January 29, 1947, Serial No. 724,971

4 Claims. (Cl. 70—224)

1

This invention relates to improvements in door locks.

Heretofore door locks have been constructed in which a key-controlled cylinder lock is mounted within the outside knob of the lock and which serves to control the operation of the lock so that unauthorized persons cannot rotate the knob to retract the bolt or latch of the lock. However, on insertion of the key into the core or plug of the lock a release mechanism may be actuated to enable the outside knob to retract the bolt. Heretofore it has been generally customary to permanently mount the cylinder lock in the outside knob by a means which is either of a permanent or semi-permanent nature. However, occasions arise when it is desirable to be able to remove the cylinder lock either for purposes of repair or replacement or to alter the tumblers to effect a change of keys.

It is a primary object of the present invention to provide a novel, simple, and advantageous manner for fastening the cylinder lock within the outside door knob in such a manner that the lock cannot be forcibly withdrawn from the knob from the outside but on the removal of the inside knob and a few readily accessible parts of the lock, the attaching means becomes readily accessible to enable removal of the cylinder lock from the outside knob to effect replacement, repair, or alterations of the tumblers to effect a key change.

With the foregoing and other objects in view, which will be made manifest in the following detailed description and specifically pointed out in the appended claims, reference is had to the accompanying drawings for an illustrative embodiment of the invention, wherein:

Figure 1 is a horizontal section through a portion of a door illustrating the door lock embodying the present invention as having been installed therein;

Fig. 2 is a sectional view taken substantially upon the line 2—2 in the direction indicated;

Fig. 3 is a sectional view taken substantially upon the line 3—3 upon Fig. 1 in the direction indicated;

Fig. 4 is a plan view of the leaf spring which constitutes the lock retaining means;

Fig. 5 is a view in side elevation of the same; and

Fig. 6 is a partial view in horizontal section similar to Fig. 1 but illustrating in dotted lines the manner in which the cylinder lock may be detached and removed.

Referring to the accompanying drawings where-in similar reference characters designate similar parts throughout, the improved door lock consists of an outside knob 10 and an inside knob 11. These knobs respectively are rotatably mounted on a stem rosette 12 and a plain rosette 13. Screws 14 extend through the plain rosette and into the

2

stems of the stem rosette 12 for attaching these rosettes to the opposite sides of the door D. A half round sleeve 15 extends into the shanks or bases of the door knobs 10 and 11 and the edges of this half round sleeve abut against shoulders 16 in the door knobs so that the half round sleeve may be rotated in either direction by either door knob when otherwise freed for rotation. Rotation of the half round sleeve in either direction is effective to retract the bolt or latch 17 by a mechanism housed within the housing 18. As this mechanism which effects a retraction of the bolt or latch 17 on rotation of the half round sleeve 15 forms no part of the present invention and may conform to conventional practice, it has not been illustrated herein.

Within the stem rosette 12 there is disposed a lock slide retainer 19 that has laterally slidable therein a lock slide 20. This slide has a recessed or notched end 21 engageable with a rib or boss 22 formed on the interior of the stem rosette 12. The lock slide 20 may be shifted into either of the positions shown in Fig. 3 by means of a plug 23, which is rigid with a rotary spindle 24 that is rotatable within the sleeve. The spindle 24 is rotatable either by a thumb key 25 that is rotatably mounted on the inside knob 11 or it may be rotated by the core or plug 26 that is rotatable within the cylinder 27 of the key-controlled cylinder lock. This lock may conform to any conventional or preferred construction having suitable tumblers operable by a key that is inserted into the core and which can serve to rotate the core relative to the cylinder 27. When the core is thus rotated its pins 28 will engage the end of the spindle 24 enabling the spindle to be turned thereby to shift the lock slide 20 from locking to unlocking position or vice-versa. As the slide retainer 19 is rigid with the outside knob 10 it will be appreciated that when the lock slide 20 is in engagement with the boss 22 that the outside knob 10 cannot be rotated. Conversely if the lock slide 20 has been shifted by the spindle 24 into unlocking position the outside knob 10 is then released to be capable of turning the half round sleeve 15 to retract the latch 17.

The above-described construction conforms generally to a conventional type of lock. The improvement resides in the manner in which the cylinder 27 of the lock mounted in the outside door knob 10 is releasably mounted therein. To this end a leaf spring 29 is rigidly attached to the body of the cylinder 27 and extends inwardly therefrom and into the shank of the outside knob. This spring may be attached to the cylinder 27 in any conventional or preferred manner. As illustrated, however, the exterior of the cylinder 27 is grooved or recessed and the portion of the spring 29 disposed in the recess is corrugated as indicated at 30. The sides of the recess are

then peened or mashed into firm engagement with the side edges of the corrugated portion of the leaf spring so as to effectively lock the spring in the recess and prevent its sliding inwardly therefrom.

Near the inner end of the leaf spring a tang 31 is struck out of the body of the spring presenting a shoulder 32 that faces outwardly and which is engageable with a shoulder 33 formed on the interior of the knob 10. As the leaf spring is biased to press outwardly or in a radial direction the shoulders 32 and 33 will be normally maintained in engagement thus retaining the cylinder 27 in the knob 10 against withdrawal. The spring 29 is preferably so arranged as to be on the opposite side of the spindle 24 from the half round sleeve 15 as illustrated in Fig. 2.

As this spring exerts reactionary force tending to tilt the cylinder lock within the knob 10 it is preferable to form a rib 34 on the interior of the knob opposite the spring 29 against which the opposite side of the cylinder 27 may bear so as to resist this tilting effect exerted by the spring.

It is to be noted that the spindle 24 is arranged in the path of inward movement of the leaf spring 29 so that as long as the spindle 24 is in position the spring 29 cannot be moved inwardly to disengage shoulders 32 and 33.

Whenever it is desired to remove the cylinder lock from the outside knob 10 this can be easily accomplished in the following manner. It is merely necessary to remove the screws 14 from the inside of the door to detach the plain rosette 13 and the inside knob 11. When this is removed the spindle 24 can be withdrawn leaving the space within the half round sleeve 15 open. A screw driver or other implement can then be inserted from the inside of the door through the space previously occupied by the spindle 24 and the inner end of the leaf spring can be engaged as illustrated in Fig. 6. By forcing the spring inwardly the shoulders 32 and 33 may be disengaged thus releasing the cylinder 27 for removal from the outside knob 10. When the lock is thus removed it may be replaced, repaired or its tumblers modified to effect a change of keys. To reinstall the lock it is merely necessary to insert the cylinder 27 into the knob 10 until it is seated therein and in so doing the leaf spring passes over the shoulder 33 until it is ultimately engaged to snap outwardly to oppose shoulders 32 and 33. The spindle 24 can then be reinserted and the knob 11 together with its rosette reapplied by means of the screws 14.

It will be appreciated from the above-described construction that the cylinder lock is firmly retained within the outside knob 10 and that no normal amount of outward pull applied to this lock will cause the shoulders 32 and 33 to disengage or cause the parts to separate. While the peening of the sides of the recess against the side edges of the corrugation 39 of the leaf spring is normally adequate to firmly retain the spring on the cylinder lock other means of attachment of the spring to the cylinder may be employed if so desired.

Various changes may be made in the details of construction without departing from the spirit and scope of the invention as defined by the appended claims.

I claim:

1. In a door lock wherein a key-controlled cylinder lock having a core is mounted in one of the door knobs thereof, a leaf spring secured to the cylinder of the lock and extending inwardly therefrom into the door knob, and a shoulder thereon engageable with the shoulder on the interior of the knob for locking the lock against removal from the knob, said spring being adapted to be forced inwardly to disengage the shoulders and enable removal of the lock, a spindle operable by the core of the lock, said spindle being arranged in the path of inward movement of the spring whereby it is first necessary to remove the spindle to clear the path of inward movement of the spring before the spring may be moved inwardly to disengage the shoulders and thus release the lock.

2. In a door lock wherein a key-controlled cylinder lock is mounted in one of the door knobs thereof, a leaf spring secured to the cylinder of the lock and extending inwardly therefrom into the door knob adjacent one side thereof, said spring having a tang struck out of the body thereof providing a shoulder facing toward the outer end of the door knob, the door knob presenting an inwardly facing shoulder engageable thereby, the spring being so arranged that on displacing it from its normal position the shoulders may be disengaged to release the cylinder lock, the interior of the knob having a rib arranged to bear against the side of the cylinder lock on the diametrically opposite side thereof from the spring.

3. In a door lock, a knob into the inner end of which a latch operating spindle extends, a lock having a core receivable in the outer end of the knob, a spring carrying a detent secured to the core, there being a shoulder on the interior of the knob engageable by the detent to hold the core against withdrawal, said detent and shoulder being so arranged with relation to the spindle that the spindle when in position in the knob prevents flexing of the spring to disengage the detent from the shoulder but when the spindle is removed the spring is afforded sufficient room to enable its being flexed to disengage the detent from the shoulder and to release the core for withdrawal from the knob.

4. In a door lock, a knob into the inner end of which a latch operating spindle extends, a lock having a core receivable in the outer end of the knob, a spring carrying a detent secured to the core, there being a shoulder on the interior of the knob engageable by the detent to hold the core against withdrawal, said detent and shoulder being arranged at the side of the spindle when the spindle is in position within the knob, the spring being engageable with the spindle to prevent its being flexed to disengage its detent from the shoulder when the spindle is in position but being adapted to be flexed to disengage the detent from the shoulder when the spindle is withdrawn.
